UNITED STATES PATENT OFFICE

166,314

CLOCK OR SIMILAR ARTICLE

Roger H. Jahncke, Geneva, Switzerland, assignor
to "Jancke S. A." Geneva, Switzerland, a company of Switzerland

Application April 27, 1951, Serial No. 14,989
In Switzerland November 6, 1950

Term of patent 3½ years

(Cl. D42—7)

To all whom it may concern:

Be it known that I, Roger H. Jahncke, a Swiss citizen and a resident of Geneva, Switzerland, have invented a new, original, and ornamental Design for a Clock or Similar Article, of which the following is a specification, reference being had to the accompanying drawing, forming a part thereof.

The figure is a perspective view of a clock or similar article embodying my new design.

I claim:

The ornamental design for a clock or similar article, substantially as shown.

ROGER H. JAHNCKE,
